UNITED STATES PATENT OFFICE.

PAUL H. LANGE, OF BRIDGEPORT, CONNECTICUT, ASSIGNOR TO THE MAX AMS MACHINE COMPANY, OF BRIDGEPORT, CONNECTICUT, A CORPORATION OF NEW YORK.

BODY-FORMING MECHANISM.

Application filed October 9, 1925. Serial No. 61,444.

This invention relates to body-forming machines such as are used for the production of bodies, as tin cans, from a blank of sheet material; and has for its main object 5 and feature the production of means for more accurately controlling the blank on the horn.

Accordingly, the invention consists of the hereinafter described features of construction, combination of parts, and arrangement of elements.

In the accompanying drawings, the invention is disclosed in a concrete and preferred form in which:

15 Fig. 1 is a general end view of the horn and the body-forming members associated therewith together with the support for said body-forming members:

Fig. 2 is an enlarged view of the support 20 for the body-forming members and associated elements, the body-forming members being omitted in this figure:

Fig. 3 is a side elevation, partly in section, 25 of the members shown in Fig. 2 and looking in the direction of arrow 3 of Fig. 2:

Fig. 4 is a vertical sectional view in the plane of line 4—4 of Fig. 3;

Fig. 5 is a detail end view of the horn and bumper:

30 Fig. 6 is a transverse sectional view in the plane of line 6—6 of Fig. 7:

Fig. 7 is a side elevation, partly in section, 35 of the horn shown in Fig. 5, showing said horn in expanded position: and

Fig. 8 is a view substantially the same as 40 that of Fig. 7 but with the horn in its collapsed position.

1 indicates a horn suitably sustained in the machine and adjacent thereto is a support 45 2 on which is pivotally carried at 3 body-forming members 4 of any desired construction. 5 indicate rods for actuating the body-forming members to fold the blank around the horn in a manner well understood. The

45 horn is composed of a number of parts, here two in number and indicated by 6 and 7; that is to say, the horn consists of two complementary halves suitably connected together and normally urged into a collapsed 50 position by suitable means such as springs 8. Suitable cam means are provided for expanding the horn and for permitting the

springs to collapse it; and, in the present instance, these means take the following form. 9 is a stationary cam member carried 55 by part 6 of the horn and having a number of cam faces, such as 10, spaced lengthwise within the horn. 11 indicates a slidable cam member having cam surfaces 12 corresponding with faces 10; and this cam member 11 60 extends lengthwise within the horn and slides upon the part 7 thereof. Suitable means are provided for reciprocating member 11 and these means are conventionally represented by rod 13 and lever 14. The 65 movement of lever 14 being a timed one, it will be seen that both the expanding and collapsing movement of the horn is timed and positively controlled because spring 8 cannot collapse the horn more rapidly than the 70 cam means will admit of. 15 indicates a clamping member arranged between the body-forming members and slidably mounted in support 2 by means of pins 16 or otherwise. Associated with this clamping member is a rod 17 extending vertically through the central bar 18 of support 2, said rod 75 having at its upper end a taper surface 19; and suitable spring means, such as 20, are provided whereby said spring means normally tend to urge the member 17 away from the surface of the horn. Timed mechanism, here represented as a rocking arm 21, is provided; and connected to this rocking arm is an actuating rod 22 slidably mounted in the 80 support 2 and having taper surface 23, complementary to taper surface 19, whereby it will be understood that when arm 21 is moved to the left (Fig. 3), rod 17 will be depressed against the action of spring 20 85 and the clamping member will firmly engage the surface of the horn. To steady and assist in guiding rod 17, there may be provided a guide bolt 24 that extends through a slot in rod 17.

90 Suitable gauging means are provided for meeting the front or leading edge of the incoming blank and to properly position it on the horn; and these means, in the present instance, take the following form. 25 indicate two slides, one at either side of the clamping member, movable in guides 26 of support 2; and these slides carry gauge members 27 which come adjacent the horn 95 100

and register the sheets as they come into position. Slides 25 are preferably carried on support 2 by means of slots 28 and pins 29, and means are provided to yield to and also to resist the impact of the blank that here assumes conveniently the form of a spring 30 carried by support 2 and acting to draw cross-bar 31 that connects both slides 25 in a direction opposite to that of the feeding movement of the blank.

It will now be understood that when a blank is fed in the usual way lengthwise to the horn, the latter is in its collapsed position and said blank comes against gauges 27 that register it, after which the clamping member descends and clamps the blank in position on the horn. Body-forming members now descend and fold the blank around the horn thereby, at the same time, bringing said blank out of the way of the gauges; and after the hooks of the blank are interlocked and the horn is expanded, bumper 32 rises and closes the seam.

I claim:

25 1. Body-forming mechanism including: a horn, body-forming members to fold a blank around the horn, a clamping member above the horn and intermediate the body-forming members to engage a blank on the horn before it is acted upon by said body-forming members, spring means for normally urging said clamping member away from the horn, and timed mechanism to overcome the action of the spring means to thereby bring the clamping member toward the horn.

2. Body-forming mechanism including: a horn, body-forming members to fold a blank around the horn, a clamping member above the horn and intermediate the body-forming members to engage a blank on the horn before it is acted upon by said body-forming members, a rod connected with said clamping member, spring means normally urging said clamping member away from the horn, an actuating rod at an angle to the first rod, and complementary taper surfaces on the two rods for imparting motion from the actuating rod to the clamping member to overcome the action of the spring means.

3. Body-forming mechanism including: a horn, body-forming members to fold a blank around the horn, gauges above the horn and intermediate the body-forming members to receive the front edge of a blank fed lengthwise of the horn, and supporting means adapted to yield in the direction of the feeding movement of the blank.

4. Body-forming mechanism including: a horn, body-forming members to fold a blank around the horn, a clamping member above the horn and intermediate the body-forming members to engage the blank on the horn before it is acted upon by said body-forming members, and gauges above the horn at either side of the clamping member and also

intermediate the body-forming members to receive the front edge of a blank fed lengthwise of the horn.

5. Body-forming mechanism including: a horn, body-forming members to fold a blank around the horn, a clamping member above the horn and intermediate the body-forming members to engage the blank on the horn before it is acted upon by said body-forming members, gauges above the horn at either side of the clamping member and also intermediate the body-forming members to receive the front edge of a blank fed lengthwise of the horn, and supporting means for the gauges adapted to yield in the direction of the feeding movement of the blank.

6. Body-forming mechanism including: a horn, body-forming members to fold a blank around the horn, a clamping member above the horn and intermediate the body-forming members to engage a blank on the horn before it is acted upon by said body-forming members, spring means for normally urging said clamping member away from the horn, timed mechanism to overcome the action of the spring means to thereby bring the clamping member toward the horn, and gauges above the horn at either side of the clamping member and also intermediate the body-forming members to receive the front edge of a blank fed lengthwise of the horn.

7. Body-forming mechanism including: a horn, body-forming members to fold a blank around the horn, a clamping member above the horn and intermediate the body-forming members to engage a blank on the horn before it is acted upon by said body-forming members, spring means for normally urging said clamping member away from the horn, timed mechanism to overcome the action of the spring means to thereby bring the clamping member toward the horn, gauges above the horn at either side of the clamping member and also intermediate the body-forming member to receive the front edge of a blank fed lengthwise of the horn, and supporting means for the gauges adapted to yield in the direction of the feeding movement of the blank.

8. Body-forming mechanism including: a horn, a support above the horn, body-forming members pivotally connected with said support, a clamping member carried by said support above the horn and intermediate the body-forming members to engage a blank on the horn before it is acted upon by said body-forming members, and gauges to receive the front edge of a blank fed lengthwise of the horn arranged on either side of the clamping member and movable therewith.

9. Body-forming mechanism including: a horn, a support above the horn, body-forming members pivotally connected with said support, a clamping member carried by said

support above the horn and intermediate the body-forming members to engage a blank on the horn before it is acted upon by said body-forming members, spring means to normally urge said clamping member away from the horn, and timed mechanism extending through said support to overcome

the action of the spring means to thereby bring the clamping member to the horn.

Signed at Bridgeport, in the county of ¹⁰ Fairfield, and State of Connecticut this 12th day of September, 1925.

PAUL H. LANGE.
